US00D973027S

(12) **United States Design Patent** (10) **Patent No.:** **US D973,027 S**
Rabello et al. (45) **Date of Patent:** **** Dec. 20, 2022**

(54) **JUNCTION BOX FOR FIBER AND POWER CABLES**

(71) Applicant: **CommScope Technologies LLC**, Hickory, NC (US)

(72) Inventors: **Jose Antonio Torres Rabello**, Orland Park, IL (US); **Nahid Islam**, Westmont, IL (US); **Marcus Jonathan Ash**, Manhattan, IL (US); **Bhavin Kadakia**, Plainfield, IL (US)

(73) Assignee: **CommScope Technologies LLC**, Hickory, NC (US)

(**) Term: **15 Years**

(21) Appl. No.: **29/686,417**

(22) Filed: **Apr. 4, 2019**

(51) LOC (13) Cl. **13-03**

(52) U.S. Cl.

USPC **D13/152**

(58) **Field of Classification Search**

USPC D13/152, 151, 123, 155, 184; D14/137; D10/96, 49; D12/213

CPC H01R 25/003; H01R 24/52; H04N 7/104; H02G 3/126; H02G 3/12

(74) *Attorney, Agent, or Firm* — Myers Bigel, P.A.

(57) **CLAIM**

The ornamental design for a junction box for fiber and power cables, as shown and described.

DESCRIPTION

FIG. 1 is a bottom perspective view of a junction box for fiber and power cables showing our design;

FIG. 2 is a front view thereof;

FIG. 3 is a rear view thereof;

FIG. 4 is a bottom view thereof;

FIG. 5 is a top view thereof;

FIG. 6 is a side view thereof; and,

FIG. 7 is an opposing side view thereof.

In the drawings, the broken lines are for the purpose of illustrating portions of the junction box for fiber and power cables which form no part of the claimed design.

1 Claim, 6 Drawing Sheets
